UNITED STATES PATENT OFFICE.

RICHARD LORD, OF CEDAR RAPIDS, IOWA.

TANK-HEATER.

1,216,583.

Specification of Letters Patent. Patented Feb. 20, 1917.

Application filed February 12, 1916. Serial No. 77,874.

To all whom it may concern:

Be it known that I, RICHARD LORD, a citizen of the United States, residing at Cedar Rapids, in the county of Linn and State of Iowa, have invented new and useful Improvements in Tank-Heaters, of which the following is a specification.

This invention relates to tank heaters and consists in certain improvements in the construction thereof as will be hereinafter fully described and pointed out in the claims.

The invention is particularly designed for use with tank heaters using lamps.

The invention is illustrated in the accompanying drawings as follows:—

Figure 1 shows a plan view of the heater with the caps removed.

Fig. 2 a section on the line 2—2 in Fig. 1.

Fig. 3 a cap for the heater.

Fig. 4 a bottom view of the cap.

Fig. 5 an enlarged view of the reservoir and one of the lamps.

Fig. 6 an enlarged view of the draft tube insert.

1 marks the lamps. As shown there are three of these lamps. These lamps are connected by the pipes 2 with a common reservoir 3, the reservoir being arranged at the center of the group of lamps. A shell 4 extends upwardly from the reservoir 3 and is supplied with a bail 5 at the top by means of which the lamps may be lowered into and lifted out of the heater.

The heater body 6 has a bottom 7, a cylindrical shell 8, a top plate 9, a central or supporting tube 10 and entrance tubes 11. The entrance tubes 11 are connected with the supporting tube 10 by the vertical slots 12 which extend downwardly to the chamber formed in the walls 8. The slots 12 are large enough to permit the pipes 2 to pass through them. The lamps, therefore, with the central support formed by the reservoir and its shell and the connecting pipes permit the introduction of the lamps downwardly through the tubes 11 and when the lamps reach the portion of the body within the shell 8 they can be swung so as to bring the lamps under the plates 9. In this manner the lamps may

be readily removed and re-inserted into the heater without disturbing the body which is of considerable weight as it should be self sinking.

Domes 13 are arranged in the plate 9 over the lamps and the chimneys 14 lead from the domes. The chimneys preferably have a bend or bends 15 to increase the heating surface of the chimneys.

A cap 16 is provided so as to cover all the openings and chimneys in the heater. The cap has the lugs 16^a which lift it slightly above the openings so that the draft is not interfered with. The cap 16 is preferably formed so as to cover all the openings and thus acts as a safety device as by reversing the cap and placing the lugs 16^a upwardly the cap closes all the openings in the heater and immediately extinguishes the fire.

In order to more certainly separate the draft flow to and from the lamps and to prevent heating of the lamps and tank, I prefer to provide the deflecting plates 17 which extend downwardly from the tube 10. To more thoroughly accomplish this purpose, I prefer to provide the draft tube insert 17^a, one of these being provided in each of the entrance tubes 11. The tube 17^a is preferably formed of sheet metal and has a metal strip 17^b secured to one side of it. The metal strip has the extension 17^c below the tube insert 17^a thus holding the tube off the bottom of the heater so as to allow the air to pass to the lamp near the bottom of the lamp. When the tube 17^a is in place, as shown in Figs. 1 and 2, the strip 17^b extends upwardly along the opening 12 thus bridging this opening. The end 17^d of the strip is bent over so as to make a convenient handle by means of which the insert may be lifted. If it is desired simply to get access to the lamps for trimming or attention the insert 17^a may be lifted into the tube 11 and held in this upper position by a projection 17^e on the strip 17^b, the projection being placed over the edge of the top of the tubes 11. Preferably the strip 17^b is just long enough to extend to the top of the tube 11.

A supply tank 18 is arranged in the shell

4. It is somewhat smaller than the shell 4 so as to permit an air passage between the walls of the tank 18 and the shell 4. The tank is closed at the top and has a valve plug 18^a screwed into the bottom. A valve passage 19 extends through the plug and this is controlled by the valve 20. A spring 21 is arranged on the stem of the valve 20, the stem having a head 22 at its bottom. Supporting lugs 23 are arranged on the plug 18^a and hold the bottom of the supply tank off the bottom of the reservoir. The height of these lugs determines the normal level of liquid in the reservoir.

15 In use the supply tank is filled in an inverted position and then turned upright, the valve forming a closure. It is then placed in the shell 4, the lugs 23 resting on the bottom of the reservoir. The length of the stem of the valve 20 is such that with the lugs 23 in this position the valve would be lifted off its seat. This permits the down-flow of fuel from the tank so long as air can pass into it to balance the air pressures. I prefer to make the bottom of the plug and the bottom of the pipe coincide because if there is a difference in the bottom level of the plug and the pipe a leakage through the joint between the plug 18^a and the bottom of the pipe may interfere with the desired level in the reservoir.

20

25

30

The fuel passes from the reservoir by way of the pipes 2 to the lamps. Each pipe 2 extends into a valve boss 24 at the bottom 35 of the reservoir. Passages 24^a are arranged in the boss and extend the opening in the pipe into the reservoir. These openings are of a size to give when fully open a proper maximum flow to the lamps. In this way a flooding of the lamps is prevented if the reservoir or heater as a whole is slightly 40 out of level. The valves 25 extend into these bosses and control these passages 24^a, each passage 24^a having a valve 25. The 45 valve 25 has a stem 26 which extends to the top of the casing so that the lamp may be regulated, if desired, from the top.

It will be readily seen that these lamps 50 may be readily removed so as to adjust and clean them. Preferably what is known as the blue flame or wickless lamps are used as they are somewhat shorter than most other lamps. The form of these lamps is not important. They may be of the type 55 using a chimney as shown or of an open type, the only requirement being that the lamp be suitable to produce a flame. It will also be observed that the supply tank may be filled and replaced without the removal 60 of the lamps and without turning out the lamps, there being a sufficient supply in the reservoir for taking care of the lamps momentarily.

I place the graduated markings 28 on

the heater at different peripheral points on 65 the heater so that by observing these with relation to the liquid in the tank 27 the user can readily observe whether the heater is level. This is quite important in that the lamps operate better and more uniformly 70 where the heater is level.

What I claim as new is:—

1. In a tank heater, the combination of 75 a lamp; a lamp support off-set from the lamp; a heater body comprising an entrance passage; a support passage having a vertically extending connection with the entrance passage; and an off-set from the entrance passage into which the lamp may be moved from the entrance passage whereby 80 the lamp may be introduced into the heater through the entrance passage while supported by the lamp support in the support passage and moved into the off-set from the entrance passage.

2. In a tank heater, the combination of 85 a lamp; a lamp support off-set from the lamp, said support forming a means of supply for the lamp; a heater body comprising 90 an entrance passage; a support passage having a vertically extending connection with the entrance passage; and an off-set from the entrance passage into which the lamp may be moved from the entrance passage whereby 95 the lamp may be introduced into the heater through the entrance passage while supported by the lamp support in the support passage and moved into the off-set from the entrance passage.

3. In a tank heater, the combination of 100 a lamp; a reservoir off-set from the lamp; a supply connection between the lamp and the reservoir; a heater body comprising an entrance passage; a reservoir passage into 105 which the reservoir may be introduced; a slot between the reservoir passage and the entrance passage through which the supply connection may be passed; and an off-set from the entrance passage into which the lamp may be moved.

4. In a tank heater, the combination of 110 a lamp; a reservoir off-set from the lamp; a supply connection between the lamp and the reservoir; a heater body comprising an entrance passage; a reservoir passage into 115 which the reservoir may be introduced; a slot between the reservoir passage and the entrance passage through which the supply connection may be passed; an off-set from the entrance passage into which the lamp may be moved; and an inverted supply tank in the reservoir, said tank leaving an air space between the walls of the tank and the reservoir.

5. In a tank heater, the combination of 120 125 a lamp; a reservoir off-set from the lamp and extending to the lamp level; a connection between the lamp and the reservoir;

a heater body comprising an entrance passage through which the lamp may be introduced; an off-set from the passage in which the lamp may be moved, the top of the off-set forming a heating plate for the lamp; and a reservoir connection forming a support for the lamp.

6. In a tank heater, the combination of a lamp; a reservoir off-set from the lamp; a supply connection between the lamp and the reservoir; a heater body comprising an entrance passage; a reservoir passage into which the reservoir may be introduced; a slot between the reservoir passage and the entrance passage through which the supply connection may be passed; an off-set from the entrance passage into which the lamp may be moved; and a chimney leading from said off-set.

20 7. In a tank heater, the combination of a plurality of lamps; a central support to which said lamps are connected; a heater body comprising a support passage; entrance passages for said lamps, said entrance passages having a vertical connection with the support passage; and off-sets from said entrance passages into which said lamps may be swung from the entrance passages.

8. In a tank heater, the combination of a plurality of lamps; a reservoir centrally located with relation to said lamps for supplying fuel to said lamps; a heater body comprising a reservoir passage into which said reservoir may be placed; entrance passages through which the lamps may be passed, said entrance passages being connected with the reservoir passage by a vertical slot; and an off-set from the entrance passages into which the lamps may be swung.

9. In a tank heater, the combination of a plurality of lamps; a support for said lamps forming a fuel connection leading to the lamps; a heater body having entrance passages into which the lamps may be introduced; off-sets from said lamps into which the lamps may be moved; valves controlling the connections to each lamp; and means for actuating the valves from the top of the heater.

50 10. In a tank heater, the combination of a plurality of lamps; a support carrying said lamps; a heater body having a series of entrance passages into which the lamps may be introduced from the top of the heater by manipulating the support; and off-sets from said passages into which the lamps may be moved simultaneously.

60 11. In a tank heater, the combination of a lamp; a support for said lamp; a heater body comprising an entrance passage; a support passage; a vertical slot; connecting support and entrance passages; an off-set from the entrance passage into which the

lamp may be moved; and a deflector plate 65 between the off-set and the support passage.

12. In a tank heater, the combination of a lamp; a lamp support off-set from the lamp; a heater body comprising an entrance passage; a support passage having a 70 vertically extending connection with the entrance passage; an off-set from the entrance passage into which the lamp may be moved from the entrance passage whereby the lamp may be introduced into the heater 75 through the entrance passage while supported by the lamp support in the support passage and moved into the off-set from the entrance passage; and an insert in the entrance passage adapted to continue the passage to a point near the bottom of the lamp.

13. In a tank heater, the combination of a lamp; a lamp support off-set from the lamp; a heater body comprising an entrance passage; a support passage having a vertically extending connection with the entrance passage; an off-set from the entrance passage into which the lamp may be moved from the entrance passage whereby the lamp may be introduced into the heater through 90 the entrance passage while supported by the lamp support in the support passage and moved into the off-set from the entrance passage; and an insert in the entrance passage adapted to continue the passage to a 95 point near the bottom of the lamp, said insert having a strip for lifting said insert, said strip bridging the connection between the entrance passage and the support passage.

14. In a tank heater, the combination of a lamp; a lamp support off-set from the lamp; a heater body comprising an entrance passage; a support passage having a vertically extending connection with the entrance 105 passage; an off-set from the entrance passage into which the lamp may be introduced into the heater through the entrance passage while supported by the lamp support in the support passage; and an insert in the entrance passage adapted to continue the passage to a point near the bottom of the lamp, said insert having a strip for lifting said insert, said strip having a shoulder for retaining the insert in a raised position.

15. In a tank heater, the combination of a lamp; a lamp support off-set from the lamp; a heater body comprising an entrance passage; a support passage having a vertically extending connection with the entrance passage; an off-set from the entrance passage into which the lamp may be moved from the entrance passage whereby the lamp may be introduced into the heater through the entrance passage while supported by the lamp support in the support passage and moved into the off-set from the entrance passage; and an insert in the entrance pas-

sage adapted to continue the passage to a point near the bottom of the lamp, said insert having a strip for lifting said insert.

16. In a tank heater, the combination of a series of lamps; a reservoir off-set from the lamps; restricted supply connections between the lamps and the reservoir; a heater body into which the lamps and reservoir may be introduced; and a supply tank for 10 supplying the reservoir.

17. In a tank heater, the combination of a heater body; a plurality of lamps arranged in the body; and marks on the body indicating in relation to a liquid surrounding the heater the position of the heater body relatively to a horizontal plane. 15

In testimony whereof I have hereunto set my hand.

RICHARD LORD.
